(57) **CLAIM**

The ornamental design for a mobile phone, as shown and described.

DESCRIPTION

FIG. 1 is a front view of a mobile phone showing-a first embodiment of the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof;

FIG. 8 is a back perspective view thereof;

FIG. 9 is a front view of the mobile phone of FIG. 1 showing an alternative configuration of use in which the mobile phone is unfolded;

FIG. 10 is a back view thereof;

FIG. 11 is a left side view thereof;

FIG. 12 is a right side view thereof;

FIG. 13 is a top view thereof;

FIG. 14 is a bottom view thereof;

FIG. 15 is a front perspective view thereof;

FIG. 16 is a back perspective view thereof;

FIG. 17 is a front view of a mobile phone showing a second embodiment of the new design;

FIG. 18 is a back view thereof;

FIG. 19 is a left side view thereof;

FIG. 20 is a right side view thereof;

FIG. 21 is a top view thereof;

FIG. 22 is a bottom view thereof;

FIG. 23 is a front perspective view thereof;

FIG. 24 is a back perspective view thereof;

FIG. 25 is a front view of the mobile phone of FIG. 18 showing an alternative configuration of use in which the mobile phone is unfolded;

FIG. 26 is a back view thereof;

FIG. 27 is a left side view thereof;

FIG. 28 is a right side view thereof;

(Continued)

FIG. 29 is a top view thereof;
 FIG. 30 is a bottom view thereof;
 FIG. 31 is a front perspective view thereof; and,
 FIG. 32 is a back perspective view thereof.
